(57) CLAIM

We claim the ornamental design for a spa shell, as shown and described.

DESCRIPTION

FIG. 1 is a top perspective view of a spa shell showing our new design;

FIG. 2 is a top plan view of the spa shell of FIG. 1; FIG. 3 is a cross-sectional view taken along line 3—3 of FIG. 2;

FIG. 4 is a cross-sectional view taken along line 4—4 of FIG. 2;

FIG. 5 is a cross-sectional view taken along line 5—5 of FIG. 2; and,

FIG. 6 is a cross-sectional view taken along line 6—6 of FIG. 2.

The bottom is plain and unornamented.
